UNITED STATES PATENT OFFICE

CARL E. EKLIND AND WILLIAM W. DARROW, OF CHICAGO, ILLINOIS, ASSIGNEES TO
CAMEL COMPANY, OF CHICAGO, ILLINOIS, A CORPORATION OF ILLINOIS

METAL CAR END

Application filed December 30, 1926. Serial No. 157,989.

This invention relates to a metal car end and concerns itself with a corrugated structure having terminal flanges into which the corrugations extend, said terminal flanges being secured to the corner posts of the car, the corrugations cushioning and rigidifying the terminal flanges, and consequently, strengthening the corner structure.

Heretofore, the corrugations in car end panels, tapered at their outer ends and terminated short of the sides of the car or the attaching margins of the panels, producing weakened sections adjacent the corners of the car. To overcome these weakened sections, it has been proposed to stamp additional short corrugations at the ends of the panels, such additional corrugations extending inwardly a short distance between the regular corrugations. Such a structure has not proved satisfactory since it interferes with the attaching margins, unduly stretches the material from which it is formed and fails to give the required rigidity and strength.

The above objections are obviated in this invention due to the merging of the corrugations into the attaching flanges whereby a strong and rigid corner structure is provided that will withstand the most severe interior impact.

The invention comprises the novel structure and combination of parts hereinafter described and more particularly pointed out and defined in the appended claims.

In the accompanying drawings, which illustrate a preferred embodiment of this invention and in which similar reference numerals refer to similar features in the different views.

On the drawings:

Figure 1 is an end elevational view of a car embodying a corrugated metal structure involving this invention.

Figure 2 is an enlarged sectional view taken upon the line II—II of Figure 1.

Figure 3 is an enlarged fragmentary sectional corner view of a metal double sheathed car embodying this invention.

Figure 4 is a view similar to Figure 3 illustrating a slight modification of corner post.

Figure 5 is a sectional corner view of a double wooden sheathed car illustrating this invention applied thereto.

Figure 6 is a view similar to Figure 5 illustrating a modified form of the invention.

Figure 7 is an enlarged corner sectional view of a single sheath wooden car illustrating this invention applied thereto.

Figure 8 is an enlarged sectional view upon the line VIII—VIII of Figure 1.

Figure 9 is an enlarged sectional view upon the line IX—IX of Figure 1.

As shown on the drawings:

In order that this invention may be readily understood, there is shown in Figure 1 an end of a car which is constructed according to this invention. It will be noted that this end comprises a pair of corner posts 1, each

of which embodies a Z bar 2 having an outwardly extending flange 3 with an overhanging lip 4. The corrugated metal panel is confined between the flanges 3. As shown the metal panel consists of a lower section 5 and an upper section 6, which are riveted together as indicated at 7. This panel is provided with longitudinal corrugations 8 and terminal flanges 9 into which the corrugations merge or extend for bracing and rigidifying the same.

The flanges 9 are riveted or secured to the outstanding flanges 3 of the Z bars with the ends of the flanges abutting the lips 4 in order to eliminate or reduce the shear on the rivets or securing means when there is an outward thrust against the end of the car.

In Figures 1 to 4, the invention is shown as applied to a double sheathed metal car. In Figures 2 and 3 the web of the Z bar 2 is shown as abutting the rear end of the post 1 with one

flange extending along the side of the car and flange 3 extending rearwardly.

In Figure 4, the rear end structure is similar to that already described with the exception that the Z bar 2 has one flange engaging

the rear end of the post 1; the flanges of the panel being secured to the webs of the Z bars with the ends thereof engaging the overhanging flange 3^a to reduce or eliminate shear with respect to the rivets or attaching means.

In Figures 5 and 6, the invention is shown as applied to a double sheathed wooden car having corner posts 10. In Figure 5, a Z bar having an outwardly extending flange

is secured to the post 10, and flange 9 of the

95

100

panel, engages the outer side of the flanges 3, being secured thereto by rivets or other means. It will be noted in Figure 5 that the ends of the panels are bent outwardly for this purpose. In Figure 6, the corrugated metal panel is provided upon its lateral ends with right-angled offset portions comprising the portion 11, which is attached to the flange 3, and a portion 12 which extends under the web of the Z bar and is secured thereto. This provided a rigid structure and the engagement of the portion 12 under the web of the Z bar 2, reduces and eliminates the shear on the rivets or attaching means.

In Figure 7, there is shown a fragmentary portion of a single sheathed car having corner posts 13 which embody Z bar 2. In this case, the metal panel is provided with a relatively long inwardly extending flange 14, which is secured to both the outstanding flange 3 of the Z bar and to the inner side walls of the bar.

The matter of attaching the panel to the top of the car is shown in Figure 8, and referring to said figure, it will be noted that the top of the panel is secured to the transverse beam 15 which extends across the car at substantially the upper end of the corner post. The manner of attaching the panel to the bottom of the car is shown in Figure 9, and in referring to said figure, it will be noted that an angle member 16 is secured to some appropriate part of the bottom of the car, preferably the floor, and the lower edge of the panel is secured to the angle 16.

It will be appreciated that in having the corrugations extend the full width of the panels, and merging or extending them into the attaching flanges of the panel, a rigid and durable structure is obtained which eliminates the weak section that heretofore existed where the corrugations terminated some distance from the ends of the panel. It will also be appreciated that in having the attaching flanges secured to one flange of the Z bars and engaging another flange at right angles to such attaching flange, the shear on the rivets or attaching means is greatly reduced or eliminated.

We are aware that many changes may be made, and numerous details of construction may be varied through a wide range without departing from the principles of this invention, and we therefore do not purpose limiting the patent granted hereon, otherwise than necessitated by the prior art.

We claim as our invention:

1. In a corrugated car end, a pair of corner posts, each embodying a Z bar, a corrugated panel having flanges attached to said Z bars, said flanges and Z bars having abutting parts tending to reduce the shear at the attached parts.

2. In a corrugated car end, a pair of opposed corner posts, each embodying a Z bar,

a corrugated metal panel having terminal flanges into which the corrugations extend, and means for securing portions of said flanges to portions of said Z bars with other portions of said flanges engaging other portions of the Z bars for the purpose set forth. 70

3. In a corrugated car end, a pair of corner posts, each embodying a Z bar, a corrugated metal panel having terminal flanges into which the corrugations merge, said flanges being secured to the web and a flange of the Z bar. 75

4. In a corrugated car end, a pair of corner posts, each embodying a Z bar, a corrugated metal panel having terminal right angled offsets secured beneath the webs and against the outstanding flanges of the Z bars. 80

5. In a corrugated car end, a pair of opposed corner posts, each embodying an angular member, and a corrugated sheet metal panel having terminal right angled attaching portions into which the corrugations merge, said attaching portions being secured to one flange of said angular members and engaging a portion at right angles thereto. 85

6. In a corrugated car end, a pair of corner posts, an angular member attached to each post with one flange thereof projecting rearwardly at substantially a right angle to the post, a corrugated metal panel having terminal flanges attached to said rearwardly directed flanges, the corrugations of said panel extending between said terminal flanges and merging into the same a sufficient extent to brace the same. 90

7. In car end structure, a pair of corner posts, having rearwardly directed flanges, and a corrugated metal panel having parts attached to said flanges, and parts in abutting relation with said flanges for resisting 105 rearward thrust, the corrugations of said panel extending between the first mentioned parts and merging into the same. 100

In testimony whereof, we have hereunto subscribed our names.

CARL E. EKLIND.

WILLIAM W. DARROW.
